UNITED STATES PATENT OFFICE.

GEORGE W. PRENTICE, OF PROVIDENCE, RHODE ISLAND.

PLACKET-CLOSURE.

No. 852,902.

Specification of Letters Patent

Patented May 7, 1907.

Application filed July 20, 1905. Serial No. 270,534.

To all whom it may concern:

Be it known that I, GEORGE W. PRENTICE, a citizen of the United States, residing at Providence, in the county of Providence and State of Rhode Island, have invented 5 new and useful Improvements in Placket-Closures, of which the following is a specification.

My present invention relates to improvements in placket - closures, and to a new 10 method of closing and securing like openings in garments in the simplest and best possible manner.

To this end my invention consists of a series of closed flat wire loops arranged at or 15 near the edges of the openings desired to be drawn together, and a lacing cord or string engaging with said closed flat loops in such manner as to have a free movement therein 20 to draw the edges of such openings together, or to permit the edges of such openings to be readily drawn apart.

My invention further consists in arranging 25 a series of closed flat wire loops upon strips of flexible material which may be cut off in suitable lengths according to the purposes required, and sewed or otherwise secured to the adjacent edges of an opening in a garment, and a lacing cord or string engaged 30 with the said loops to provide ready means for closing or opening the edges of said placket or like opening.

My invention has for its objects, first, to 35 provide a placket fastening which shall be of as simple a nature as possible and which shall effectually hold the placket of a woman's skirt, or like opening, securely closed and in such manner as to assume a neat and tidy appearance without indicating its presence as attached to the skirt; second, to construct a placket-closure which can be easily manipulated by the wearer to open and close 40 said placket or like opening, and third, to construct a placket-fastening of flexible strips 45 or material having a series of flat wire loops secured thereto at equal distances apart in such manner that said strips may be readily cut off into lengths required to fit the edges of various sized openings.

In the accompanying drawings, wherein 50 similar letters of reference indicate corresponding parts, Figure 1, represents a front elevation of a placket having my improved fastening applied thereto, with the parts in a closed position. Fig. 2, a similar view, with 55 the edges of the placket drawn apart, or in an

open position. Fig. 3, a detail view of a strip of flexible material having a series of flat loops applied thereto, and Fig. 4, a similar view of two lengths cut therefrom, and 60 connected together at their lower ends ready for attachment to the placket or like opening of a garment.

In carrying out my invention, a series of flat closed loops A, preferably formed from 65 properly tempered wire, and bent to provide a closed loop upon the surface of the material with arms B, having their extremities bent down at right angles to form setting prongs, are applied at or near each edge of the placket 70 or like opening of a garment, as disclosed more fully in Fig. 1, of the drawings. The main object to be attained in my invention being to have said loops lie flat and smooth upon the surface of the material to 75 which they may be attached, and yet capable of being slightly raised at their free ends to admit the lacing cord or string.

Another feature of my invention is to provide a placket-closure comprising flexible 80 strips, of suitable material, having a series of closed flat loops A, applied thereto and at suitable distances apart thereon, in such manner that the said strips may be sold as an article of trade, and afterward cut into suitable 85 lengths by the purchaser to adapt the same to the edges of various sized plackets or other like openings.

In either event the nature and objects of the invention are substantially the same, and 90 the adjacent edges of the placket, or other like opening, being provided with the series of closed flat loops, a suitable lacing cord or string D, is passed therethrough, from bottom to top, in the manner illustrated in the 95 drawings, and the mere act of drawing tightly upon the free ends of said lacing cord or string serves to close the placket, or other like opening, and the cord being passed around the waist of the wearer convenient to 100 be manipulated, can be tied in position to hold the parts securely together. By simply releasing the tie, the edges of the placket can be readily drawn apart to open the same, the lacing cord or string running freely 105 through said loops to accomplish this result.

Having thus described my invention, what I claim as new and desire to secure by Letters Patent, is:—

1. A placket-closure, comprising two flat 110 flexible strips each provided with a series of closed flat wire loops, arranged to lie flatwise

upon said strips and having a lacing cord engaged therewith, in combination with the adjacent edges of a placket or other like opening, substantially as described.

5. 2. A placket-closure, comprising a series of closed wire loops, each having an attaching table and setting prongs, and arranged opposite each other on the adjacent edges of a placket or other like opening whereby the front of each loop may be raised for the insertion of a lacing cord, substantially as described.

10. 3. In a placket closure, and in combination therewith, a flat flexible strip of material

provided with a series of closed flat wire loops, each formed of a single piece of wire and arranged to lie flatwise upon said strip, and a pre-determined length of said strip attached to each side of the placket closure, substantially as and for the purpose specified.

15. In testimony whereof I affix my signature in presence of two subscribing witnesses.

GEORGE W. PRENTICE.
